UNITED STATES PATENT OFFICE

MARTIN J. OLSON, OF ISHPENMING, MICHIGAN.

ORGAN-TUNER'S KEYBOARD-PLAYER.

1,051,156.

Specification of Letters Patent. Patented Jan. 21, 1913.

Application filed November 12, 1910. Serial No. 591,956.

To all whom it may concern:

Be it known that I, MARTIN J. OLSON, a citizen of the United States, residing at Ishpeming, county of Marquette, and State of Michigan, have invented new and useful Improvements in Organ-Tuners' Keyboard-Players, of which the following is a specification, reference being had to the accompanying drawings, forming a part thereof.

10 The purpose of this invention is to provide means for operating the keys of a pipe organ or similar musical instrument at a distance from the keyboard, being particularly intended for use in the tuning and re-15 pairing of organs.

It consists of the features described, and shown in the drawings, as indicated in the claims.

In the drawings—Figure 1 is a sectional elevation of the organ-key actuating device. Fig. 2 is a sectional elevation of the switch-board. Fig. 3 is a partial sectional plan view of the key-actuating devices. Fig. 4 is the electrical wiring diagram for the device. Fig. 5 is a partial front elevation of the switch-board. Fig. 6 is a detail of the locking device in operative position, the release position being indicated in dotted lines. Fig. 7 is a wiring diagram indicating the 30 mode of connecting the series of control magnets, 5, in a common circuit with the stroke-giving magnet, 10.

In a pipe organ, as is well understood, the parts requiring attention for tuning are positioned where the tuner cannot manipulate them and at the same time reach the manual keys, and as constructed, many of the pipes are often far removed from the key-board, being placed wherever space is afforded for 40 them in the building. Consequently, the tuning of such organs at present involves the employment of a helper for the skilled organ-tuner, who shall remain at the key board and operate the keys for sounding 45 various notes as required by the tuner. The present device is designed to dispense with the services of such a helper, since it provides means electrically connecting the organ key-board with an operating key-board at 50 any distance to which an electric current can be efficiently conducted.

Briefly, the device consists of two mechanisms,—viz: an electro-magnetically-operated actuating mechanism designed to be 55 mounted over the organ key-board for actuation of the organ keys, and a structure of

the nature of a switch-board constructed to resemble the organ key-board,—that is, having its switch keys made in the form of organ keys and arranged in similar order. 60 A single flexible cable, made up of a multiplicity of wires and of any desired length, constitutes the electrical connection between these two mechanisms.

The key-operating mechanism will be first 65 described. A series of bell-crank strikers, 1, having horizontal and vertical arms, and fulcrumed in bifurcated brackets, 2, secured to the main housing, 3, of the mechanism, are positioned with their horizontal arms, 1^a, 70 extending respectively over the keys A of the manual of an organ, in substantially the position assumed by the fingers of the performer. To the vertical arm 1^b of each bell-crank is coupled a thrust rod, 4, having a 75 soft-iron armature, 4^a, secured to its under side. Directly under this armature is mounted an electro-magnet 5, designed to draw the rod downward when the circuit is closed, such movement being resisted by a 80 spring 4^b on the rod. An actuator for the strikers in the form of a bar, 6, extending throughout the length of the organ key-board, and mounted in an approximately 85 vertical position, is fulcrumed at 6^a near its lower edge, and connected by a link 7 and bell crank 8 to the armatures 9, 9, of stroke-giving electro-magnets, 10, 10, mounted exteriorly on the main housing 3. These 90 stroke-giving electro-magnets, 10, 10, are 95 preferably, but not necessarily, of the solenoid type, so that their armatures 9, 9, are plungers. Downward movement of the rod 4, under the influence of its magnet 5, brings 100 its free end, 4^c, in position for encounter 105 with the upper edge, 6^b, of the actuator bar 6, when the latter is rocked about its fulcrum. Thus each of the rods, 4, constitutes a disengageable connector for transmitting the movement of the bar, 6, to one of the 110 key strikers, and except when they are under the influence of their respective magnets, 5, these rods are biased out of connecting position by means of their springs, 4^b. The electrical switch devices are so arranged that the magnet 5 is first energized to draw the rod 4, corresponding to any key which is to be operated, into position for such encounter, and almost simultaneously, the circuit through the solenoids 10, 10, is closed, 115 causing movement of their plungers 9, 9, and of the motor bar 6 through its me-

chanical connections above noted. In this way, the bell-crank-striker 1 is rocked sufficiently to depress the organ key for sounding the note desired.

5 The amount of angular swing of the actuating striker 1 may be varied by changing the position of a stop rail 11, shown adjustably connected with the top of the housing, and secured by a set screw 12 at the 10 limit of depression of the organ key. As the striker approaches this limit a pawl 13, biased upward by its spring 13^a, snaps into position to engage the lock bar 14 which, like the motor bar 6, is of substantially the 15 same length as the organ key-board. The electrical circuit may then be opened without releasing the organ key, so that a sustained note may be produced without draining the source of electrical energy, which, 20 for cheapness and convenience, would usually be of the portable cell type. One or more keys having been thus held locked in depressed position as long as required by the tuner, their release is effected by closing 25 the circuit through a magnet 15, which operates similarly to the above-described magnets, but to move a thrust link 16, provided with an armature 16^a, and pivoted to a rocker arm 17, rigidly secured to the lock 30 bar 14. The switch-key used for closing the circuit of the magnet 15 is arranged similarly to the above described switch keys for also closing the circuit for energizing 35 the solenoids 10, 10, so that as soon as the thrust link 16 has been brought into position for encounter of its projecting tooth 16^b with the upper edge 6^b of the motor bar 6, said bar is actuated as before, but this 40 time to rock the edge 14^b of the lock bar 14 out of engagement with the pawl or pawls 13 engaged with it. The strikers, 1, being thus released from their depressed position, rock back to their initial position, allowing 45 the organ keys to follow, and shut off the pipes which they control. It may be understood that while a separate thrust rod 4 and magnet 5 are required to correspond with each key of the organ key-board, only a single link 16 and magnet 15 are necessary for 50 release. A number of organ keys may be successively depressed, and since each is locked in depressed position, a chord may be thus produced, if desired, but all the keys will be released by a single movement of the 55 release switch key. After their operation, the lock bar 14 and thrust link 16 are returned to normal position by their respective springs 14^b and 16^b.

As already stated, the operating keys of 60 the electrical switch-board controlling the device may be made in the form of an organ manual, so that the operator has nothing new to learn in addition to his knowledge of the organ. This "dummy" manual may be 65 of considerably reduced dimensions, how-

ever, for convenience of use in close quarters; and even the resemblance to the organ key-board is not essential, since any form of switch-board with the switches marked to show their correspondence to the keys of the organ may be employed. As illustrated, the electrical contacts are of the flat spring type, this being comparatively cheap, and efficient enough for use with the small current obtained from a few portable "dry" cells. 70 None of the contact elements are secured to their actuating key 18, but are mounted directly under the latter, upon a foundation board, 19, insulating blocks, 20 and 21, being provided at the secured ends, and a spacing block 22 between the free ends of the movable members 23 and 24. The spacing block, 25, is also provided between the stationary contact members 26 and 27, to prevent other than the desired contacts. A release switch, 28, of similar construction, is shown mounted separately from the actuating switches in the front rail 29 of the frame. Since when the contact devices are made as shown, a single movement of the switch key closes 80 two circuits, very slight priority of contact in one circuit as compared with the other cannot be depended upon to avoid mechanical confusion in the actuating mechanism. For this reason, a certain amount of 85 "lost motion" is preferably introduced in the connections of the motor bar, 6, and connecting thrust bars 4 and 16, so that the latter will certainly be drawn downward by their controlling magnets before the motor bar 6 has moved into position for encounter with whichever of said thrust bars has been brought into action; that is, the operations are rendered concurrent rather than strictly 90 simultaneous.

At one end, the foundation board 19 is provided with a series of spring contact clips 30, arranged as compactly as practicable, and each properly connected with some contact member of the switch-board. Co-operating plug pins 31 are similarly arranged and mounted in a removable board 32, and wires from the respective pins form a cable 33 which is led out from the board 32 to the key-actuating mechanism mounted, 100 as described, at the organ manual. At this end, the cable enters a similar removable board 34, provided with plug-pins 35, to which the respective wires are connected, and which fit into a series of spring contact clips 36, mounted on the housing 3 of said key-actuating mechanism, and electrically connected with their respective magnets. Proper connections from the solenoids 10, 10, and the smaller magnets 5 and 15, with 105 their respective batteries, indicated in the wiring diagram only, complete the list of the parts necessary to the operation of the device.

In Fig. 2, there is shown an index button, 130

37, carried in an inverted T-slot in the casing of the switch-board manual, and slideable therein throughout the length of said manual. This button may be set opposite the 5 switch-key corresponding to the organ note with which the tuner is working, as a convenient means of identification. A set of removable legs 38 for the switch-board or "dummy" manual, and screw-clamps 39 for 10 attaching the actuating mechanism to the cheeks B of the organ key-board, are also shown. The two principal members of the apparatus,—viz: the key-actuating mechanism mounted in the main housing 3, and 15 the "dummy" key-board with its switch connections mounted on the foundation board 19, are conveniently made of substantially the same horizontal dimensions, so that they may be assembled for carrying, 20 back to back, in a case whose depth, being substantially the sum of the heights of said two principal members, will accommodate in the remaining space the cable with its terminal plug boards and the detached legs 25 and disconnected battery cells. Thus, the apparatus is readily portable, and becomes a part of the tuner's regular working equipment.

I claim:

30 1. A device for the purpose indicated comprising, a plurality of key strikers arranged for registration, respectively, with the keys of a keyboard, an actuator, a motor operatively connected therewith, a disengageable 35 connector corresponding to each striker adapted to transmit movement thereto from the actuator and standing normally out of connecting position, a motor device corresponding to each connector and arranged 40 for moving it into connecting position, a dummy manual having a plurality of keys corresponding, respectively, to the aforesaid strikers, and connections controlled by said keys for energizing their respective motor 45 devices and the actuator motor.

2. A device for the purpose indicated comprising, a series of key strikers arranged and adapted to engage the respective keys of a keyboard, an actuator, a disengageable connector for each striker adapted to transmit movement from the actuator to said striker and standing normally out of connecting position, a series of manual control keys separately and selectively operable at will, and 50 connections therefrom to the actuator and to the respective connectors whereby each key is adapted for concurrently effecting movement of a connector into connecting position and movement of the actuator for operation of the corresponding striker.

3. A device for the purpose indicated comprising, a series of key strikers arranged and adapted to engage the respective keys of a keyboard, an actuator, a disengageable 55 connector for each striker adapted to trans-

mit movement from the actuator to the striker and standing normally out of connecting position, a motor operatively connected with the actuator, separate means for moving each connector into connecting position, and a series of manual control keys separately and selectively operable at will, each connected with the connector-moving means for one connector and with the motor, and adapted for concurrently energizing 75 said means and the motor, respectively.

4. A device for the purpose indicated comprising, a series of key strikers arranged and adapted to engage the respective keys of a keyboard, an actuator, a disengageable 80 connector for each striker adapted to transmit movement from the actuator to such striker, a motor operatively connected with the actuator, means yieldingly holding each connector out of connecting position, a series 85 of electro-magnets each positioned for drawing one of the connectors into connecting position, a series of manual control keys separately and selectively operable at will, and connections from said keys to said 90 magnets, respectively, to the motor adapting each key for concurrently energizing one of said magnets and the motor, respectively.

5. A device for the purpose indicated comprising, a key striker adapted to engage 95 key of a keyboard, an actuator, a disengageable connector adapted to transmit movement from the actuator to the striker and standing normally out of connecting position, an electromagnet and an armature 100 therefor operatively connected to move the actuator, a second electromagnet arranged for drawing the connector into connecting position, a manually operable controller and connections for concurrently energizing said 105 magnets.

6. A device for the purpose indicated comprising, a key striker adapted to engage a key of a keyboard, a motor device, means adapted to transmit movement therefrom to the striker for depression of the latter, a locking pawl and an abutment adapted to coöperate therewith, one of said elements being carried by the striker, means for yieldingly forcing the pawl into engagement 115 with the said abutment when the striker is in depressed position, and means for energizing the motor at will.

7. A device for the purpose indicated comprising, a key striker adapted to engage a 120 key of a keyboard, a motor device, connections adapted to transmit movement therefrom to the striker for depression of the latter, a locking pawl and an abutment adapted to coöperate therewith, one of said 125 elements being carried by the striker, means for yieldingly forcing the pawl into engagement with the said abutment when the striker is in depressed position, means adapted for releasing the striker from said 130

- lock, a manually operable controller adapted for energizing the motor at will, a manually operable controller, and connections to effect actuation of the lock-releasing means 5 at will.
8. A device for the purpose indicated comprising, a key striker adapted to engage a key of a keyboard, an actuator, a disengageable connector adapted to transmit movement from the actuator to depress the striker and standing normally out of connecting position, a locking pawl and an abutment adapted to coöperate therewith, one of said elements being carried by the 10 striker, means for yieldingly forcing the pawl into engagement with the said abutment when the striker is in depressed position, means for releasing the striker from said lock, including a disengageable connector adapted to transmit movement from the aforesaid actuator, and controlling devices connected, respectively, to the said disengageable connectors and to the actuator, each manually operable at will and arranged 15 20 25 for effecting concurrently the movement of its connector into connecting position and the movement of the actuator.
9. A device for the purpose indicated comprising, a key striker adapted to engage a key of a keyboard, means for depressing the striker, means for locking said striker in depressed position, comprising a pawl on the striker, a movable stop-rail positioned to 30 35 40 45 50 55 60 engage the pawl when the striker is depressed, an actuator, a disengageable connector adapted to transmit movement from said actuator to the movable stop-rail for disengagement of the pawl, a controlling device manually operable at will and connections for concurrently effecting the movement of said connector into connecting position and the movement of the actuator.
10. A device for the purpose indicated comprising, a key striker adapted to engage a key of a keyboard, means for depressing the striker, an automatic lock adapted to retain the striker in depressed position, means for releasing the striker from said lock, including an actuator and a disengageable connector adapted to transmit the movement of the actuator, an electro-magnet arranged for drawing said connector into connecting position, a motor operatively connected to the actuator, a manually operable controlling device and connections for concurrently energizing said magnet and said motor at will.

In testimony whereof, I have hereunto set my hand, at Ishpeming, Mich., in the presence of two witnesses, this 9th day of Nov. 1910.

MARTIN J. OLSON.
